UNITED STATES PATENT OFFICE.

EDGAR W. GENT, OF NEW YORK, N. Y., ASSIGNOR TO WESTERN ELECTRIC COMPANY,
INCORPORATED, OF NEW YORK, N. Y., A CORPORATION OF NEW YORK.

ELECTRICALLY-OPERATED TIMING APPARATUS.

1,391,947.

Specification of Letters Patent. Patented Sept. 27, 1921.

Application filed January 29, 1921. Serial No. 441,091.

To all whom it may concern:

Be it known that I, EDGAR W. GENT, a citizen of the United States, residing at New York city, in the county of New York, State 5 of New York, have invented certain new and useful Improvements in Electrically-Operated Timing Apparatus, of which the following is a full, clear, concise, and exact description.

10 This invention relates to timing devices and more particularly to a device for timing the duration of an electrical impulse or series of such impulses.

Its object is a device which will be automatically set in motion by an initial electrical impulse, which will be automatically stopped upon the receipt of the last impulse of a series and which will give a direct indication of the elapsed time between the initial and final impulse or between the beginning and the end of the impulse period.

The invention in the form herein disclosed, is adapted to the timing of a series of current impulses such as are produced 25 by impulse transmitters employed in automatic telephone exchange systems. In its preferred form it comprises a device having a natural period of motion, as for example, a torsion pendulum which is electromagnetically released for operation by the initial 30 impulse of a series.

After release the pendulum swings through a definite arc depending upon its natural period of motion and is automatically stopped when the last impulse of the 35 series to be measured takes place. A scale carried by the pendulum gives a direct indication of the arc through which the pendulum has rotated and may be calibrated from 40 the time constant of the moving system to give a direct indication of the elapsed time between the first and last impulse of the series.

The invention will be more clearly understood from a consideration of the drawings, in which Figure 1 is a front elevation, part in plan, and part in section, of the device in its preferred form; Fig. 2 is a sectional view taken along the line 2-2 of Fig. 1, 50 showing in detail the construction of the rotatable mass; Fig. 3 is a sectional view, taken along the line 3-3 of Fig. 1, showing in detail the transfer cam, the restorer arm, and

its associated parts, and the spring pile-up; Fig. 4 is a side elevation of the stepping 55 magnet; Fig. 5 is a sectional view showing the preferred method of making the suspension wire fast to the rotatable mass; and Fig. 6 shows the circuit connections of the 60 apparatus.

In the preferred form of the invention, there is provided a frame 1 supporting the protecting tubes 2. A protecting metal sheet 3, supported on the frame 1, serves as a covering. Within the two metal tubes 4, 65 fastened to the frame 1 in any approved manner, extends the suspension wire 6, being held taut by means of studs 7 to caps 9. Cap 9 at the upper end of the apparatus is held immovable by means of the screw 5. A rotatable mass 10 is centrally supported by the suspension wire 6, as at 11, in such a way that the wire is made fast to the mass at this point. Two guiding or alinement members 12, preferably of brass, project 75 from the mass 10 as is shown more clearly in Fig. 5, and serve to insure the alinement of the suspension wire 6. The scale 13 is marked off on the mass 10 as hereinafter described, and the pointer 14, mounted on the 80 frame 1, is adapted to indicate the pulse rate of the apparatus on test. A tension spring 15 serves to exert a tension on the sliding head 9, the pin 8 of which is adapted to move in the slot 16; this head or cap thus 85 exerts a tension on the suspension wire 6 at all times.

The upper portion of the scale is laid out in degrees and the lower portion, which is associated with it, indicates the pulse rate 90 per second. The rotatable mass, in this particular case is adjusted, as hereinafter described, to swing 33½ swings per minute, or 50 swings in 1½ minutes. Since the lowest number on the scale is 5, in order for the instrument to show a rate of five impulses per second, it would be necessary for the mass to swing the full 180 degrees from the normal position. The time interval for such a swing is 1.8 seconds, which is obtained by 100 multiplying .2 seconds, this being the time for one impulse, by nine, as the instrument actually measures nine complete impulses, since the tester is set into motion upon the opening of the first impulse, and is stopped 105 by the opening of the tenth impulse. The

lower scale is then laid out with the aid of the upper scale in accordance with the law of harmonic motion.

The stepping magnet 17 is provided with a 5 commutator 18, and a brush 19 adapted to engage any one of four open segments 20 of the said commutator; a ratchet wheel 21 is also provided together with its associated stop pawl 22, and driving pawl 23, whereby 10 the commutator 18 will be stepped around with the ratchet wheel 21.

Associated with the stepping relay is the transfer cam 24 which may be rotated by means of the restorer handle 25 which moves 15 through the slot 26 in the base 1. A restorer arm 27, adapted to engage with the restorer pin 28 carried by the rotatable mass 10, terminates in the lever 29 which also supports the restorer handle 25; the lever 29 20 carries a spring 30 adapted to engage either of the two open segments 31 in the transfer cam 24, by means of which the said cam may be rotated during the setting operation, as is more clearly shown in Fig. 3. The spring 25 member 32 of the transfer spring pile-up 33 is adapted to engage the cam 24 in such a way that as the cam is rotated, a contact will be made which will close the stop magnet circuit.

30 The stop magnet 34 is provided with an armature 35 upon which is mounted a stop pawl 36 which is adapted to engage the toothed edge of the rotatable mass 10 to control the motion of the said mass. The mass 35 10 is provided with a pair of counter-balance weights 37 and an adjusting screw 38 for adjusting the position of these weights. Thus, by means of this screw, the counter-balance weights may be adjusted to give the rotatable mass the desired number of swings per 40 minute.

A window 39 is positioned in the outer cover 3 so that the scale 13 may easily be read when the cover is in place.

45 The operation of the timing device may be more clearly understood by referring to Fig. 6: The apparatus inclosed in the square A forms no part of the present invention, but consists of a dial 43 in circuit with any 50 approved stepping relay, and its associated apparatus. When it is desired to test the dial, the instrument is first set at normal by moving the lever 29, by means of the handle 25, 180 degrees from the normal position, and then restoring it to normal. As this is 55 done, the spring member 32 of the spring pile-up 33 is pressed upward by the surface of the cam 24 to make with its associated contact. This closes the stepping magnet circuit, and 60 the commutator 18 will automatically be stepped around by the ratchet 21, and its associated pawl 23 until one of the four open segments 20 falls below the brush 19 before the handle 25 has been rotated the forward 65 180 degrees. As the brush 19 forms a con-

tact in any open segment 20, the stop magnet circuit will be closed, the armature 35 will be attracted by the magnet 34, and the stop pawl 36 will release the mass 10, permitting the said mass to rotate. The restorer arm 70 27 will engage the restorer pin 28 of the rotatable mass 10, forcing the mass to the desired position. At the end of the forward 180 degrees, the transfer spring 32 is operated, opening the stop-magnet circuit, and 75 allowing the armature 35 to fall back and cause the stop 36 to engage the teeth of the mass, bringing it to rest. Handle 25 is now restored to normal and the indicator is set to receive a series of impulses from a dial 80 which may be located near at hand or in the subscriber's station. The dial 43 will be operated to dial ten impulses, the key 44 having first been closed so that the pulse relay 45 and its associated relay 46 may be 85 operated by the incoming pulses. At the opening of the first impulse, the relay 45 will be energized, attracting the armature 47 thereby causing the relay 46 to be energized. The relay 45 will immediately be deenergized 90 at the end of the first impulse, but the relay 46, being of the slow release type, remains energized long enough to attract the armature 48, causing the stepping magnet circuit to open, thereby notching around the 95 commutator 18 one tooth and closing the circuit through the commutator and the stop magnet, releasing the stop on the mass and permitting the mass to swing. The set of incoming impulses causes the stepper to step 100 correspondingly and the opening of the tenth pulse causes the commutator to be stepped to an open segment 20, opening the stop magnet thereby stopping the moving mass. The pointer 14 will then indicate on the scale 105 105 the pulse rate per second of the dial 43.

What is claimed is:

1. In a timing device, an oscillatory mass having a predetermined period of oscillation, means for storing energy in said 110 device, electromagnetic means for releasing said mass to permit free movement thereof, electromagnetic means for stopping said mass, and means carried by said mass for giving a direct indication of the elapsed 115 time between said starting and stopping.

2. A device for timing a series of electrical impulses comprising an oscillatory mass having a predetermined period of motion, means for storing energy in said device, 120 means responsive to the initiated impulse of a series for releasing said mass and permitting its free motion, means responding upon the cessation of said series of impulses for stopping the movement of said mass, and means on said device for indicating the length of the time interval between said initial impulse and the cessation of impulses.

3. A device for timing a series of electrical impulses comprising an oscillatory mass 130

having a predetermined natural period of motion, means for storing energy in said mass, a release magnet responsive to the initial impulse of the series for releasing said mass and permitting its free movement, means acting upon the cessation of impulses to arrest the motion of said mass, a scale carried by said mass and a pointer coöperating therewith to give a direct indication 10 of the length of the time interval between the said initial and final impulses.

4. In a device for timing a series of electrical impulses, a torsion pendulum comprising an oscillatory mass and suspension means therefor, means for placing said suspension means under an initial torsional tension, a serrated disk carried by said mass, an electromagnet, a holding pawl controlled thereby and coöperating with said serrated disk 20 to hold said mass in its deflected position or to arrest the motion of said mass, a second electromagnet and circuit connections therefor whereby the second electromagnet is made to respond to the impulses to be measured, a step-by-step mechanism operated by said second electromagnet, a commutator operated thereby for causing the energization of said first mentioned electromagnet upon the initiation of a series of impulses and permitting the pendulum to swing upon receipt of the first impulse of a series, and for deenergizing said first mentioned electromagnet and stopping the pendulum upon the receipt of the last impulse 30 35 of a series, and means carried by said pendulum for indicating the time duration of said series of impulses.

5. In a device for timing a series of electrical impulses, a length of wire under tension, a mass supported by said wire and normally held against rotation, means operated by the first impulse of a series to release said mass to permit free movement thereof, and means acting at the end of said 45 series to stop said mass.

6. In a device for timing a series of electrical impulses, a length of wire under tension, a mass supported by said wire, a catch member to prevent rotation of said mass, and means automatically controlling said 50 catch member whereby said mass will be re-

leased and allowed to swing at the first of a series of impulses, and stopped at the last impulse of said series.

7. In a device for timing a series of electrical impulses, a time recording mechanism, a catch member to prevent the operation of said mechanism, a stepping magnet operated by said electrical impulses, and a stop magnet controlled by said stepping magnet 55 60 to operate said catch member at the first and last of said series of impulses to respectively start and stop said time recording mechanism.

8. In a device for timing a series of electrical impulses, a length of wire under tension, a rotatable mass supported by said wire, a catch member to prevent rotation of said mass, a stop magnet adapted to control said catch member, and a stepping magnet for 70 75 operating said stop magnet at the first and last of said series of impulses to respectively start and stop said mass.

9. In a device for timing a series of electrical impulses, a length of wire under tension, a mass supported by said wire and normally held against rotation, a catch pin mounted on said mass, a restorer member adapted to engage said catch pin to rotate said mass, and means whereby the operation 80 85 of said restorer member will automatically serve to release said mass to rotate with said restorer member and cause said mass to stop in a position set to receive a series of incoming electrical impulses.

10. In a device for timing a series of electrical impulses, a length of wire under tension, a mass supported by said wire, a stop magnet adapted normally to hold said mass against rotation, a stepping magnet adapted 90 95 to control said stop magnet, and means whereby the stepping magnet will step in accordance with the impulses of the impulse sender on test, the first of said impulses serving to release said mass to rotate freely, and the last of said impulses causing the stepping magnet to operate the stop magnet to bring the said mass to rest.

In witness whereof, I hereunto subscribe my name this 22 day of January, A. D., 1921. 100

EDGAR W. GENT.
